UNITED STATES PATENT OFFICE.

MARTIN W. CARR, OF SOMERVILLE, MASSACHUSETTS.

DESIGN FOR AN EASEL.

SPECIFICATION forming part of Design No. 17,231, dated March 29, 1887.

Application filed December 3, 1886. Serial No. 220,638. Term of patent 54 years.

To all whom it may concern:

Be it known that I, MARTIN W. CARR, a citizen of the United States, residing at Somerville, in the county of Middlesex, State of Massachusetts, have invented and produced a new and original Design for Easels or Picture-Supports, of which the following is a full, clear, and exact description, reference being had to the accompanying drawing, forming a part of this specification, in which the figure is an isometrical perspective view of this newly-designed easel.

The leading feature of my design consists of a series of standards, A, representing stems of the calla-lily plant converging toward their upper extremities and diverging in curves above said point of convergence, their extreme tips representing the flowers of said plant, and a standard, B, converging to the point of convergence of the standards A and passing upward therefrom, its tip representing a flower of the said plant.

Having thus explained my design, what I claim is—

1. The design for an easel, as herein shown and described, consisting of a series of standards representing stems of the calla-lily plant converging together toward their upper ends and diverging in curves above said point of convergence, their extreme tips representing the flowers of said plant. 25

2. The design for an easel, as herein shown and described, consisting of a series of standards representing the stems of the calla-lily plant converging together toward upper ends and diverging in curves above said point of convergence, their extreme tips representing the flowers of said plant, and a standard converging to the point of convergence of said series of standards and passing in a straight 35 line upward therefrom, its tip representing a flower of the said plant. 40

MARTIN W. CARR.
